US0D1028415S

(12) United States Design Patent (10) Patent No.: US D1,028,415 S
(45) Date of Patent:  May 28, 2024

(54) SCARF

(71) Applicant: CHRISTIAN DIOR COUTURE, Paris (FR)

(72) Inventor: Maria Grazia Chiuri, Paris (FR)

() Term: 15 Years

(21) Appl. No.: 35/516,824

(22) Filed: Mar. 20, 2023

(80) Hague Agreement Data

Int. Filing Date: Mar. 20, 2023

Int. Reg. No.: DM/227912

Int. Reg. Date: Mar. 20, 2023

Int. Reg. Pub. Date: Apr. 7, 2023

(30) Foreign Application Priority Data

Sep. 27, 2022 (EM) 009186307-0025

(51) LOC (14) Cl. 02-05

(52) U.S. Cl.

USPC D2/500; D2/600

(58) Field of Classification Search

USPC D2/500-508, 600, 605

CPC A41D 23/00; A41D 25/00

See application file for complete search history.
